CIRCUIT BREAKER LATCH

Robert W. Thomas, St. Clair Shores, Mich., assignor to
I-T-E Circuit Breaker Company, Philadelphia, Pa., a
corporation of Pennsylvania

Filed Aug. 1, 1958, Ser. No. 752,630

8 Claims. (Cl. 200—116)

The instant invention relates to electric switches and is particularly directed to means for obtaining a predetermined automatic type setting for a switch of the type described in the Elwood T. Platz Patent 2,385,727.

In the switch of the above identified patent a single main spring is utilized to provide the forces for snap-action opening and closing of the switch contacts and also provides the pressure for a releasable latch which comprises a bimetallic element whose deflection is effective to cause release of the latch.

The main spring at one end bears against the switch casing and the other end against the contact arm upon which the movable contact is mounted and which also carries the bimetallic element. The line of action of the spring is such as to produce a component of force which returns the latching portion of the bimetal to its proper cool position when the switch is turned On. This same component of force holds the contact arm in a reference position against a cam plate while the bimetal deflects because of heating and cooling in its normal functional operation.

It has been found that for the large main springs required of high capacity switches, the increased spring forces tend to tilt the contact arm so that the latching position of the bimetal becomes unpredictable. In order to obtain a stable and reproducible latch distance, the main spring must be made to assume a shape or position such as to provide an additional force or pressure at the back end of the contact arm.

This is accomplished by providing the end of the casing with an inclined seat. Thus the spring is caused to buckle against the contact arm and exert a component of force in the proper direction at the back end thereof.

Accordingly, a primary object of the instant invention is to provide novel means whereby a predictable latch bite of a bimetallic element may be obtained.

Another object is to provide means whereby the main spring of an electric switch is utilized to stabilize the positions of the switch components.

Still another object is to provide a sloping seat for one end of a coil-type main spring whereby the spring is buckled to exert a force component directed to urge the movable contact carrying arm against the switch casing.

These as well as other objects of the instant invention shall become readily apparent after reading the following description of the accompanying drawings in which:

Figure 1 is a perspective view of an electric switch.

Figures 2-4 are front elevations with the front of the casing removed showing the elements of the switch. In Figures 2 and 3 the elements are in the Off and On positions, respectively, while in Figure 4 the elements are shown at the end of an inward stroke of the handle after the elements are in the Off position.

Figures 5 and 6 are perspective views of the operating handle.

Figure 7 is a perspective view of the casing.

2

Figure 8 illustrates the switch elements separated from one another.

Figures 9-11 are vertical cross-sections taken through planes at right angles to the front elevations of Figures 2-4. Figures 10 and 11 illustrate the manual latch releasing action.

Figure 12 is a horizontal cross-section of the switch.

Figures 13 and 14 are perspective views showing the indicator in the On and Off positions respectively.

10 Figure 15 is a perspective view of the switch elements mounted in the casing with the switch in the On position.

Figure 16 is a fragmentary horizontal cross-section of the switch illustrating the latching position of the bimetal tip.

15 Figure 17 is a perspective view of a wedge shaped insert which serves as a seat for the main spring.

The drawings show the switch as comprising a cup shaped casing 10 having an open front closed by a plate or cover 11 secured thereto, as by screws (not shown).

20 The back of the case is formed with two openings, 12 and 13, for line and load terminals 14-15.

In an opening 16 reciprocates a handle or actuator 17 formed as a push button. A groove 18 of the handle receives a tongue 19 of the casing, with operating clearances provided between the side walls 20-21 of the

25 handle and the left and right side surfaces 22 and 23 of the casing interior; the back and front surfaces 24-25 of the handle slidably engage the back surface 26 of the casing and the surface of the cover.

30 A cross ledge 28 of the casing has at 30, a seat for a coiled compression spring 31 which biases the handle outwardly, the upper end of the spring seating in a socket 32 of the handle back, and against a lug 33 thereof, which lug is adapted to cooperate with the upper end of a spring

35 receiving socket in the back of the casing to limit outward motion of the handle; another limitation or stop for handle movement is provided by a handle lug 34 formed for cooperation with a pawl 35; still another limitation or

40 stop for handle movement is provided by a handle lug 36 formed to cooperate with a casing lug 37.

The pawl 35, later to be described in detail, restrains outward travel of the handle, but only during the closed circuit position, merely holding the handle in an intermediate or "on" position, and preventing the handle from

45 going all the way out to its open circuit or "off" position.

Handle position is relied upon to indicate the position of the circuit closing parts within the casing. The handle is furthest out in the open circuit or "off" position; it is held by the pawl 35, not so far out in its circuit closed

50 or "on" position; when the handle is pressed down from the closed circuit position for opening the circuit, it travels into the case a slight distance so as to release itself from the pawl 35 above mentioned, whereupon the spring 31 moves the handle well out of the casing to the "off" position, movement being stopped by parts 36-37.

Movement of the handle is utilized to operate an indicator in the form of a plate 38 having an actuating lug 40 and having "on" and "off" markings. The plate is disposed within an undercut portion 41 of the handle

60 so that only one of the two markings of the plate is visible at any time through a window slot 42 of the handle. The lug 40 rides in a camming groove 43 formed in the upper portion of the back of the casing.

As the handle moves up and down, the plate 38 moves

65 back and forth alternately in the undercut 41 to expose its "on" and "off" markings alternately to view through the slot 42. When the handle is full out or in the "off" position, the lug 40 of the indicator plate 38 is in the upper or back part of the groove 43 and the "off" marking is exposed through slot 42.

As the handle is moved down, plate 38 slides down with the handle and for-

70

ward of the slot 42 to present its "on" marking to slot 42. In the "on" position of the handle, lug 40 of plate 38 is in that part of groove 43 which causes plate 38 to have its "on" marking exposed at slot 42; and only when the handle is in the extreme out or "off" position will the lug 40 be in the upper or rear-most part of groove 43 so that the "off" marking of plate 38 is exposed to slot 42.

Since the handle occupies but one circuit open position, whether the circuit be opened manually or by automatic overload release, the handle has but two rest positions, "on" and "off," and these two positions indicate the conditions of the circuit controlling parts of the breaker.

The circuit controlling parts of the switch include a stationary contact 44 disposed under and against a ledge 45 of the casing and formed integral with line terminal 14. A U-shaped fibre arc shield 46 engages a hooked stop lug 47 of the casing. Adapted to make butt contact with the stationary contact 44 is the contact portion 48 of a movable contactor 49 having an L-shaped contact arm 50 which is riveted at 51 to a bimetal strip 52, with rivet 51 being formed as a pin to provide a loose pivotal connection between the contactor 49, comprising parts 50-52, and a cam plate 53 of insulation, the latter having an elongated slot 54 receiving a stop lug 55 formed on the back of the casing. Pawl 35 is an integral part of plate 53.

An operating spring 56 has its lower end in a seat 57 of the casing and its upper end surrounding a spring lug 58 formed from the contact arm 50. Spring 56 functions to rotate arm 50 counter-clockwise for circuit opening on the axis of pivot pin 51 when the latching hook 60 forming the free end of the bimetal strip 52 is released from engagement with the holding abutment, i.e., the latching edge 61 of the plate 53. Such release of latch 60 from the holding means 61 is effected either automatically, by the warping of the bimetal 52 on overload, or manually, by the camming action provided by a sloping cam 62 of and integral with the handle. When this cam is pushed down it cams latch hook 60 off the abutment or holding means 61, to permit the contact arm to be rocked counter-clockwise relative to the plate 53 by the spring 56, for circuit opening.

Spring 56 also biases contactor 50 and plate 53 upwardly, and when the latch holds, provides the force to move contact 48 towards and press contact 48 against contact 44.

In a circuit opening action (Figures 2-3), spring 56, through pivot axis 51, will slide the plate 53 upwardly, with the latter guided by the casing; the engagement of the lower edge of plate slot 54 with casing stop 55 will limit such movement of the plate. That stop 55 will at that time function as a pivot for the plate 53 and since the line of action of spring 56, through axis 51, is to the left of that pivot, plate 53 will rock clockwise about stop 55, under the spring biasing force (Figure 2). Pawl portion 35 of plate 53, which normally holds handle 17 against extreme outward movement, will thereupon be caused to release its hold on lug 34 of handle 17 to release that handle and permit it to travel to the full "off" position, under the bias of spring 31.

In the "on" position, however, that plate 53 is so positioned by the spring 56 and by the casing walls that pawl 35 engages handle lug 34 to hold the handle against full outward travel to "off" position.

A flexible connector 65, looped around the bimetal strip 52, has one end 66 secured to the free end of that bimetal strip and has its other end 67 secured to that part of the load terminal 15 that was thrust into the casing through the load terminal hole 13. This connector completes the circuit between the two terminals 14-15, employing only that part of the contact arm 50 extending from contact 48 to pivot pin 51 for carrying current.

The end of pivot pin 51 near the back of the casing is seated within a casing pocket 68, elongated to permit the pin 51 to slide up and down.

A lug 70 bent down from terminal 15, is the part to which the end 67 of connector 65 is secured.

To restore the parts to the circuit closing position (Figure 3), the handle 17 is pushed down as far as it will go and it will go down far enough, first, to cause the notch 71 of a cam part thereof to engage a resetting lug 72 of the plate 53, and second, to cause the pin 51 to slide downwardly. That part of plate 53 connecting lug 72 and pin 51 acts as a translator. The contactor 49 will move downwardly with pin 51 until arm 50 reaches a resetting stop 47 of the casing, although in many instances

15 that stop will have been engaged by the arm 50 at the end of the circuit opening movement of the arm. Continued downward movement of the handle and continued downward movement of the lug 72, and pin 51, will cause the contactor to engage stop 47 and rock clockwise,

20 on axis 51, far enough to cause latch 60 to slide over or overtravel beyond holding edge 61 (Figure 4), for relatching. The release of the handle by the operator at that time will free the handle to be moved to its outward position by the spring 31 (Figure 3), and as the handle moves outwardly, the spring 56 will act on the contactor.

25 The contactor will rock slightly counterclockwise and assume its final "on" position, with latch 60 engaging holding edge 61, and with contact 48 abutting contact 44 under pressure of spring 56. Plate 53 will rock counterclockwise to place lug 72 out of the path of cam 71.

30 The space 74 between ledge 28 and the line terminal ledge 45 provides a pocket for the flexible connector 65, which, thus being pocketed, is restrained from fouling the moving parts of the device to impede their operation.

35 At 75 is illustrated a calibrating tip of the contactor, engaging the plate 53, and determining the position of the latch tip 69 relative to the latch surface 61.

40 When the contactor is manufactured, the position of the flexible tip 60 relative to rigid tip 75 may not be moved for calibration and to obtain an accurate positioning of tip 69 with respect to tip 75; since the position of rigid tip 75, formed to engage the edge of plate 53, is not variable, calibration of the position of tip 60 relative to tip 75 automatically insures calibration of the position of tip 60 relative to plate 53 and automatically insures calibration of the amount of overlap of tip 60 on edge 61 of plate 53 and automatically insures calibration of the amount of warping of tip 60 from edge 61 of plate 53 that is required to unlatch the breaker.

45 In switches adapted for low current capacity the switch construction as heretofore described is quite satisfactory.

50 In order to provide a force component for latching contactor 49 to cam plate 53, the force line of action of main spring 56 is tilted downward toward lug 58 of contactor 49, from the case 10. With relatively light springs, this force component is sufficient to provide the latching action required but not enough to upset the stability of contact arm 50 which is supported by case formations 55 and 98. To further facilitate this stability, a hold down spring 96 may be positioned around rivet 51 to bear against case 10 and contact arm 50. However, the force of spring 96 must be maintained at a low value

55 since this force also increases the frictional sliding components between contactor 49 and the surfaces of the casing 10 and cam plate 53 upon which contactor 49 bears when the switch is tripped Off and latched On.

60 For higher capacity switches, stronger main springs are required with the latching force component thereof tending to upset the stability of contact arm 50 in a manner which causes the portion 95 of contact arm 50 to lift or tilt away from case formation 55. The remaining two points of support at case formation 98 and tip 75

of contact arm 50 create a pivot line 97 about which contact arm 50 will rotate. Thus, if the portion at 95 lifts or tilts upward with respect to Figure 15, the bimetal latch tip 60, being mechanically tied to contact arm 50 and being on the opposite side of pivot line 97, will tilt downward. This tilt causes an undesirable and variable increase in the bite of the bimetal latch tip 60.

In order to maintain the stability of contact arm 50, main spring 56 is shaped or distorted so as to exert a component of force upon contact arm 50 which urges portion 95 thereof toward cam plate 53. This is accomplished by having one end of main spring 56 seated upon a sloping formation 90 (Figure 15) formed integrally with case 10 which causes main spring 56 to buckle against contact arm 50 and urge portion 95 against case formation 55.

Instead of utilizing an integrally formed sloping seat 90, a wedge shaped insert 89 (Figure 17) may be placed in case recess 57 (Figure 7) which provided a level seat for main spring 56.

With this construction, latch tip 60 will always assume a predetermined position with respect to latch surface 61 of cam plate 53.

Although I have here described preferred embodiment of my novel invention, many variations and modifications will now be apparent to those skilled in the art, and I therefore prefer to be limited, not by the specific disclosure herein, but only by the appending claims.

I claim:

1. An electric switch comprising a casing, a cam plate, a contactor, an operating handle, and a main spring; said cam plate, said contactor, and said main spring being disposed within said casing; a fixed contact secured to said casing and a movable contact carried by said contactor and engageable with said fixed contact; said contactor being operatively connected to said cam plate; said handle being engageable with said cam plate for movement of said contactor and said cam plate to positions wherein said main spring is effective to latch said contactor to said cam plate and to bring said contacts into engagement; said handle being engageable with said contactor for movement thereof to a position wherein said main spring is effective to bring about the disengagement of said contacts; seating means for said main spring constructed and positioned whereby said main spring is positioned to exert a component of force urging said contactor toward said cam plate to assume a predetermined position with respect thereto when said contactor is latched to said cam plate.

2. An electric switch comprising a casing, a cam plate, a contactor, an operating handle, and a main spring; said cam plate, said contactor, and said main spring being disposed within said casing; a fixed contact secured to said casing and a movable contact carried by said contactor and engageable with said fixed contact; said contactor being operatively connected to said cam plate; said handle being engageable with said cam plate for movement of said contactor and said cam plate to positions wherein said main spring is effective to latch said contactor to said cam plate and to bring said contacts into engagement; said handle being engageable with said contactor for movement thereof to a position wherein said main spring is effective to bring about the disengagement of said contacts; said main spring comprising a coiled element; seating means for said coiled element constructed and positioned whereby said coiled element is buckled at a point intermediate the ends thereof; said point being in engagement with said contactor whereby said contactor is urged to a stabilized position with respect to said casing when said contacts are in engagement.

3. An electric switch comprising a casing, a cam plate, a contactor, an operating handle, and a main spring; said cam plate, said contactor, and said main spring being disposed within said casing; a fixed contact secured to said casing and a movable contact carried by said contactor

and engageable with said fixed contact; said contactor being operatively connected to said cam plate; said handle being engageable with said cam plate for movement of said contactor and said cam plate to positions wherein said main spring is effective to latch said contactor to said cam plate and to bring said contacts into engagement; said handle being engageable with said contactor for movement thereof to a position wherein said main spring is effective to bring about the disengagement of said contacts; said main spring comprising a coiled element; said coiled element being buckled at a point intermediate the ends thereof; said point being in engagement with said contactor whereby said contactor is urged to a stabilized position with respect to said casing when said contacts are in engagement; said coiled member being seated at one end against an inclined formation of said casing and at the other end against said contactor.

4. An electric switch comprising a casing, a cam plate, a contactor, an operating handle, and a main spring; said cam plate, said contactor, and said main spring being disposed within said casing; a fixed contact secured to said casing and a movable contact carried by said contactor and engageable with said fixed contact; said contactor being operatively connected to said cam plate; said handle being engageable with said cam plate for movement of said contactor and said cam plate to positions wherein said main spring is effective to latch said contactor to said cam plate and to bring said contacts into engagement; said handle being engageable with said contactor for movement thereof to a position wherein said main spring is effective to bring about the disengagement of said contacts; said contactor including an L-shaped contact arm having said movable contact at the free end of a first leg thereof; said main spring having one end thereof in contact with a second leg of said contact arm and a second end thereof in contact with a seat formation of said casing; said seat formation comprising an inclined surface whereby said main spring is positioned to exert a component of force urging the junction of said first and said second legs toward said cam plate whereby said contactor assumes a predetermined position with respect to said cam plate when said contactor is latched thereto.

5. An electric switch comprising a casing, a cam plate, a contactor, an operating handle, and a main spring; said cam plate, said contactor, and said main spring being disposed within said casing; a fixed contact secured to said casing and a movable contact carried by said contactor and engageable with said fixed contact; said contactor being operatively connected to said cam plate; said handle being engageable with said cam plate for movement of said contactor and said cam plate to positions wherein said main spring is effective to latch said contactor to said cam plate and to bring said contacts into engagement; said handle being engageable with said contactor for movement thereof to a position wherein said main spring is effective to bring about the disengagement of said contacts; said contactor including an L-shaped contact arm having said movable contact at the free end of a first leg thereof; said main spring having one end thereof in contact with a second leg of said contact arm and a second end thereof in contact with a seat formation of said casing; said seat formation comprising an inclined surface whereby said mainspring is positioned to exert a component of force urging the junction of said first and said second legs toward said cam plate whereby said contactor assumes a predetermined position with respect to said cam plate when said contactor is latched thereto; said seat formation being formed integrally with said casing.

70 6. An electric switch comprising a casing, a cam plate, a contactor, an operating handle, and a main spring; said cam plate, said contactor, and said main spring being disposed within said casing; a fixed contact secured to said casing and a movable contact carried by said contactor and engageable with said fixed contact; said

contactor being operatively connected to said cam plate; said handle being engageable with said cam plate for movement of said contactor and said cam plate to positions wherein said main spring is effective to latch said contactor to said cam plate and to bring said contacts into engagement; said handle being engageable with said contactor for movement thereof to a position wherein said main spring is effective to bring about the disengagement of said contacts; said contactor including an L-shaped contact arm having said movable contact at the free end of a first leg thereof; said main spring having one end thereof in contact with a second leg of said contact arm and a second end thereof in contact with a seat formation of said casing; said seat formation comprising an inclined surface whereby said main spring is positioned to exert a component of force urging the junction of said first and said second legs toward said cam plate whereby said contactor assumes a predetermined position with respect to said cam plate when said contactor is latched thereto; said seat formation comprising an insert member adapted to nest within a recess of said casing.

7. An electric switch comprising a casing, a cam plate, a contactor, an operating handle, and a main spring; said cam plate, said contactor, and said main spring being disposed within said casing; a fixed contact secured to said casing and a movable contact carried by said contactor and engageable with said fixed contact; said contactor being operatively connected to said cam plate; said handle being engageable with said cam plate for movement of said contactor and said cam plate to positions wherein said main spring is effective to latch said contactor to said cam plate and to bring said contacts into engagement; said handle being engageable with said contactor for movement thereof to a position wherein said main spring is effective to bring about the disengagement of said contacts; said contactor also including a bimetallic element having a free end engageable with a latching edge of said cam plate for latching said contactor to said cam plate; said element being deformed, when heated to a predetermined temperature, to unlatch said contactor from said cam plate and permit said main spring to disengage said contacts independently of the position of said handle; seating means for said main spring constructed and positioned whereby said main

spring is positioned to exert a component of force urging said contactor toward said cam plate to assume a predetermined position with respect thereto when said contactor is latched to said cam plate.

8. An electric switch comprising a casing, a cam plate, a contactor, an operating handle, and a main spring; said cam plate, said contactor, and said main spring being disposed within said casing; a fixed contact secured to said casing and a movable contact carried by said contactor and engageable with said fixed contact; said contactor being operatively connected to said cam plate; said handle being engageable with said cam plate for movement of said contactor and said cam plate to positions wherein said main spring is effective to latch said contactor to said cam plate and to bring said contacts into engagement; said handle being engageable with said contactor for movement thereof to a position wherein said main spring is effective to bring about the disengagement of said contacts; said contactor also including a bimetallic element having a free end engageable with a latching edge of said cam plate for latching said contactor to said cam plate; said element being deformed, when heated to a predetermined temperature, to unlatch said contactor from said cam plate and permit said main spring to disengage said contacts independently of the position of said handle; said main spring being positioned to exert a component of force urging said contactor toward said cam plate to assume a predetermined position with respect thereto when said contactor is latched to said cam plate; said contactor including an L-shaped contact arm having said movable contact at the free end of a first leg thereof; said main spring having one end thereof in contact with a seat formation of said casing; said seat formation comprising an inclined surface whereby said main spring is positioned to exert a component of force urging the junction of said first and said second legs toward said cam plate whereby said contactor assumes a predetermined position with respect to said cam plate when said contactor is latched thereto.
